UNITED STATES PATENT OFFICE.

LOUIS E. SUTTER, JR., OF BEAVER FALLS, PENNSYLVANIA.

INDICATING DEVICE.

1,232,120.

Specification of Letters Patent.

Patented July 3, 1917.

Application filed January 24, 1917. Serial No 144,227.

To all whom it may concern:

Be it known that I, LOUIS E. SUTTER, Jr., a citizen of the United States, residing at Beaver Falls, in the county of Beaver and State of Pennsylvania, have invented a new and useful Indicating Device, of which the following is a specification.

This invention relates to indicating devices.

10 The object is to provide an indicating device which is particularly adapted for household use by indicating to deliverymen or dealers the amount of a certain commodity desired, or to impart other information, 15 without the necessity for personally communicating with said dealer.

Another object is to provide a device of this character, which may be supported directly upon a pane of glass, in a window 20 or a door, within the view of a dealer, in such manner as to indicate to him just what the wishes of the householder are, without loss of time or unnecessary labor.

Another object is to provide an indicator 25 of simple construction, which is susceptible of manufacture at such low cost, as to render the same valuable as an advertising medium, which may be given away by dealers, having their advertisements im- 30 printed upon the device.

A full and complete understanding of the invention will be obtained upon a careful consideration of the following detailed description, taken in connection with the accompanying drawings forming a part of 35 this specification; it being understood that while the drawing shows a practical form of the invention, the latter is not confined to strict conformity therewith, but may be 40 changed or modified, so long as such changes or modifications mark no material departure from the salient features of the invention, as specifically pointed out in the claims hereto appended.

45 In the drawings, in which like reference characters designate like parts in each of the several figures:

Figure 1 is a front elevation of the device, shown applied to a window.

50 Fig. 2 is a rear elevation thereof.

Fig. 3 is an enlarged central sectional view, showing the device applied to a pane of glass.

55 Fig. 4 is a side view of the combined pivot and vacuum cup.

In the drawings there is illustrated an in-

dicating device having the improvements combined therein, and comprising a circular base member 1 which, in the present instance, is formed of heavy cardboard, 60 though some other suitable material may be substituted therefor. The circular base member 1 is preferably provided with diagonally disposed outstanding tongues 2 arranged at the top and bottom thereof, the 65 upper tongues being preferably provided with apertures 3 for the purpose of conveniently supporting the device upon a nail, or the like, when the device is not in use.

A sight opening 4 is provided in the base 70 member 1, and is preferably, though not necessarily, formed by cutting out an arcuate portion at the top of the base member, for the purpose of exposing certain indicia, as will be explained. The circular base mem- 75 ber 1 is provided with a central pivotal post 5, which is formed of rubber, and passed through a suitable opening 6 formed in the base member 1 and having upon its rear end a head 7, and upon its front end a somewhat 80 enlarged head 8 formed in the usual shape of a vacuum cup for the purpose of applying the device to a window pane, in a well known manner. These heads are formed integral with the pivot post 5 and are, con- 85sequently, susceptible of considerable yielding movement.

A rotatable disk 9 is mounted upon the shank of the pivot post 5 in rear of the circular base member 1, and is adapted to be 90 rotated in either direction, to bring certain indicia, printed thereon, into register with the sight opening 4 in the base member 1. The squeezing action of the heads 7 and 8 of the pivotal post 5 tends to force the base 95 member 1 and the disk 9 together, so that the frictional engagement therebetween, will hold the disk in its adjusted position.

A circular series of finger-receiving openings 10 are formed in the disk 9 in spaced 100 relation to the pivot 5, and are adapted to receive the finger of the operator in order to facilitate the rotary movement of the disk 9, to bring any desired character into view through the opening 4. Other indicia 105 11 corresponding to the indicia upon the front of the card are provided in rear thereof adjacent to the finger openings 10, so that by bringing the desired number or other indicia to a midway position between 110 the top tongues 2, the desired number or indicia is exposed in front, without the ne-

cessity of removing the device from its location upon a window pane.

A slot 12 is formed in the rotary disk 9 and extends from one of the finger-receiving openings to a central point, and there connects with the pivot-receiving opening 13 formed in the center of the disk 9. The slot 12 tapers toward the central opening 13 and is for the purpose of permitting the passage 10 of the pivot post 5 therethrough, when assembling the parts. The head 7 of the pivot post will pass freely through the finger opening 10, and the shank of the post is then forced through the tapering slot 12 15 when the shank of the post will enter the central opening 13 of the disk 9 and slightly expand therein, thus preventing the accidental displacement of the disk 9.

The characters employed in the present 20 showing of the invention are in the form of a series of numbers 14 and are adapted to indicate the number of pounds of ice desired by the householder. The base member, in the present showing, has the words 25 "Leave" printed to one side of the sight opening 4 and "LBS" to the other side of said sight opening, and the word "Ice" beneath the same. Any other arrangement or combination of words may, of course, be 30 employed, such, for instance, as would be necessary to indicate the desired amount of milk, or other commodity.

From the foregoing it will be seen that an extremely simple indicating device has been 35 designed, which may be easily and quickly applied to a pane of glass in a door or window, and which may be easily adjusted by the householder, from within, to indicate to a deliveryman, outside of the house, just 40 what is desired of him, thus resulting in a great saving of time and labor.

The remainder of the space upon the front 45 of the base member 1 is well adapted for advertisements, as indicated at 15, or any other desired information may be applied thereto. Thus the device is well suited as an advertising medium.

What is claimed is:—

1. An indicating device comprising a 50 front member provided with a sight opening, a rotatable disk pivotally mounted on the back of the front member and having indicia imprinted on the front face thereof, said indicia being adapted to be brought 55 into register with said sight opening, a centrally located compressible pivot having a head at either end, said heads yieldably

holding the front member and disk together to maintain certain of the indicia within view, and a vacuum cup formed in the head 60 located at the front of the device to attach the same to a window pane.

2. An indicating device comprising a front card provided with a centrally located rubber pivot, a sight opening formed in the 65 front card in spaced relation to the pivot, an adjustable indicating card mounted for rotation on the pivot, in rear of the front card, and provided with a circular series of characters on the front face thereof and in 70 alinement with the said sight opening, heads formed on the ends of the pivot to cause a frictional engagement between the abutting faces of the cards, and a vacuum cup provided in the front face of the front head. 75

3. An indicating device comprising a base member provided with a flexible, centrally-disposed pivot having a head at each end, a vacuum cup formed in that head in front of the base member, a sight opening provided in the said member, a rotatable indicating card, mounted on the pivot, in rear of the base member, and having a circular series of characters on the front face thereof, said card having a series of finger openings provided therein, whereby the card may be rotated to bring certain of the indicia into register with the sight opening, and characters provided on the back adjacent to the finger openings and corresponding to the 90 characters on the front.

4. An indicating device comprising a base member provided with a flexible, centrally-disposed pivot having a head at each end, a vacuum cup formed in that head in front of the base member, a sight opening provided in the said member, a rotatable indicating card, mounted on the pivot, in rear of the base member, and having a circular series of characters on the front face thereof, said 100 card having a series of finger openings provided therein, and a slot connecting one of the finger openings with the central pivot opening to permit of the entrance of the adjacent head of the flexible pivot, when assembling the device. 105

In testimony, that I claim the foregoing as my own, I have hereto affixed my signature in the presence of two witnesses.

LOUIS E. SUTTER, JR.
